UNITED STATES PATENT OFFICE

170,963

EARRING OR SIMILAR ARTICLE

Michael Chernow, New York, N. Y.

Application July 21, 1953, Serial No. 26,060

Term of patent 7 years

(Cl. D45—9)

To all whom it may concern:

Be it known that I, Michael Chernow, a citizen of the United States and residing at New York, in the county of New York and State of New York, have invented a new, original, and ornamental Design for an Earring or Similar Article, of which the following is a specification; reference being had to the accompanying drawings, forming part thereof, and in which

Fig. 1 is a front elevational view of an earring or similar article showing my new design,

Fig. 2 is a rear elevational view thereof, with the conventional clip element shown in dot and dash lines,

Fig. 3 is a side elevational view thereof with the conventional clip element also shown in dot and dash lines, and

Fig. 4 is a bottom elevational view thereof.

I claim:

The ornamental design for an earring or similar article, substantially as shown.

MICHAEL CHERNOW.
